UNITED STATES PATENT OFFICE

SYDNEY E. JOHNSON AND SIDNEY I. KORNHAUSER, OF LOUISVILLE, KENTUCKY, ASSIGNEES TO STANDARD FURNACE AND RANGE COMPANY, OF LOUISVILLE, KENTUCKY, A CORPORATION OF KENTUCKY

DISSECTING TABLE

Application filed September 17, 1928. Serial No. 306,368.

Our invention relates to a new type of dissecting table particularly adapted for use in human anatomical laboratories. In laboratories it is frequently necessary or desirable to leave the cadaver undisturbed on the dissecting table when not being worked upon. Ordinarily this procedure is not advisable due to the rapid deterioration of the cadaver.

10 An object of our invention is to provide a dissecting table which may easily be converted into a humidor for preserving the cadaver when not being worked upon.

15 A further object of our invention is to provide a dissecting table which is simple and economical in construction and which permits the person doing the dissecting to work with the maximum freedom and comfort.

20 To accomplish these and other objects our dissecting table is provided with covers which when closed form a closed compartment or humidor over the platform of the table and when open fold neatly under the 25 table and out of the way of the knees of the person working at the table.

Our invention will be better understood from the following description taken in connection with the accompanying drawing in 30 which Figure 1 is a perspective view of our new dissecting table showing one of the covers closed and the other cover open; and Figure 2 is a sectional view in perspective of a portion of the covers in closed position.

35 Referring to the drawing, 10 denotes the platform of our table mounted upon the rectangular frame 11 which is supported by uprights 12 and footpieces 13 having suitable braces 14. The uprights 12 are connected together near their lower ends by the rod 15 which strengthens the frame structure and also serves as a foot rest. The platform 10 is in the form of a shallow pan and adapted 40 to contain a small amount of suitable preserving fluid. Within the pan-shaped platform 10 is an unsecured strip of corrugated sheet metal 16 having perforations 17. The corrugations in the sheet metal strip 16 act 45 to support the cadaver out of contact with

the preserving fluid contained in the platform 10.

The covers 18 secured to the rectangular frame 11 by hinges 19 are adapted to close over the platform 10 to form a closed compartment or humidor. The free edges of the covers 18 are upturned and provided with a tongue member 20 and a groove 21 respectively which cooperate to form a relatively tight joint when the covers 18 are in closed position. The ends of the covers 18 are provided with flanges 22 which fit over the ends of the platform 10. The U-shaped fastening member 23 secured to the upturned edge of one of the covers 18 is adapted to fit over both of the upturned edges of the covers 18 when they are in closed position. The covers 18 are provided with suitable handles 24 to facilitate handling. The hooks 25 mounted on the ends of the covers 18 co 55 operate with suitable stays 26 mounted on the uprights 12 to secure the covers 18 in open position.

From the foregoing description it will be seen that we have provided a convenient, 60 practical and sanitary dissecting table. The pan-shaped platform 10 is adapted to contain any suitable preserving fluid and supports the corrugated sheet 16 which is removable to permit cleaning. The perforations 17 in the corrugated sheet 16 permit 65 passage of the fumes from the preserving fluid in the platform 10 and the corrugations serve to hold the cadaver out of contact with the preserving fluid.

When the table is in use, that is, when dissecting is being carried on, the covers 18 are swung downward and fastened in open position as described. It is readily seen that the shape of the covers 18 permit the maximum freedom for the knees of the person working on the cadaver. When work is suspended the covers 18 are closed over the top of the pan-shaped platform 10 and the cadaver to form a relatively airtight compartment or humidor which retains the fumes arising from the preserving fluid and the cadaver is preserved unmolested until such a time as work on the cadaver is continued.

In constructing our table we prefer to use 100

sheet metal in the platform and covers and angle iron in the frame although other material may be used. Also, we prefer to use some non-corrosive metal, such as Monel metal, in the platform and the corrugated sheet so that they will not be affected by the preserving fluid.

While we have described a particular embodiment of our invention, it will be obvious to those skilled in the art that various modifications may be made without departing from the spirit of our invention and we therefore desire to cover all such modifications as fall within the scope of our invention which is set forth in the appended claims.

What we claim as new and desire to secure by Letters Patent of the United States, is,—

1. A dissecting table comprising a frame, a pan-shaped platform mounted on said frame, and covers hinged to said frame and cooperating to form a relatively air tight hood over the top of said platform when in closed position, and swingable outwardly and downwardly into depending relation to their hinges so as to be out of the way when in open position.

2. In a dissecting table the combination of a frame, a pan-shaped platform mounted on said frame, a perforated corrugated member disposed within said pan-shaped platform, covers hinged to said frame and adapted to cooperate with the said platform to form a closed compartment when in closed position, and adapted to swing into depending relation to their hinges under the platform when in open position and means for fastening the covers in both open and closed position.

3. A dissecting table comprising a frame structure supporting a pan-shaped platform adapted to contain preserving fluid, a corrugated sheet metal member disposed within said pan-shaped platform adapted to support a cadaver out of contact with said preserving fluid, perforations in said sheet metal member permitting passage of fumes from said preserving fluid and covers hinged to said frame and cooperating with the pan-shaped platform to form a humidor compartment for confining the fumes for preservative purposes.

In testimony whereof we have affixed our signatures, Sept. 13, 1928.

SYDNEY E. JOHNSON.
SIDNEY I. KORNHAUSER.
